UNITED STATES PATENT OFFICE.

THOMAS WHITE, OF TALMAGE, KENTUCKY.

COUPLING.

1,336,326.

Specification of Letters Patent.

Patented Apr. 6, 1920.

Application filed October 5, 1918. Serial No. 257,076.

To all whom it may concern:

Be it known that I, THOMAS WHITE, a citizen of the United States, residing at Talmage, in the county of Mercer and State of Kentucky, have invented certain new and useful Improvements in Couplings, of which the following is a specification.

This invention relates to the rolling stock for railways, and more especially to the 10 couplings employed between cars; and the object of the same is to produce an improved coupling of the pin and link type and which will work successfully in conjunction with the link of an ordinary car 15 coupling on another car.

A further object is to produce a coupling of this type in which the pin can be raised to uncouple the same by any suitable means and from a remote point.

20 A third object is to provide means for holding the pin raised at all times and therefore throwing the coupling out of action temporarily.

Other objects will appear as the following 25 specification develops, and reference is made to the drawings, wherein:—

Figure 1 is a perspective view of this coupling as a whole,

Fig. 2 is a central longitudinal sectional 30 view, and

Fig. 3 is an enlarged detail of the latch showing the latter in dotted lines as turned aside.

Fig. 4 is a detail perspective view of the 35 dog *per se*.

Fig. 5 is a vertical section on the line 5—5 of Fig. 2.

Fig. 6 is a fragmentary detail perspective 40 view of the portion of the mechanism illustrated in Fig. 1 with the pin removed.

The draw bar B has an enlarged head H at its front end, the same being provided with a mouth M as usual, and into this mouth is adapted to be projected a link (not shown) forming part of a companion car coupling or part of an ordinary car coupling which uses such a link. The object of the present invention is to produce a pin coupling for such a link, with means wherefore the pin is automatically raised by the entrance of the link and then dropped into it, but cannot be raised to uncouple from the link without manual effort. Coming now to the details of the present invention, a skeleton framework 1 is erected on the upper side of the draw head and is pierced with a hole 2 in line with similar holes through

the top and bottom of the head H, and in which moves a pin 3 having an enlargement or collar 4 at about its mid-length and a link or eye 5 at its upper end and to which may be attached a chain or cord for raising the pin to uncouple it from the link. Pivoted at 6 on the top of the framework is a plate 7 having a notch 8 constituting a latch, the same being held in normal position by a spring catch 9 as shown in Fig. 1 but capable of being turned aside when this catch is raised, as shown in dotted lines in Fig. 3. At this time the pin 3 may be raised and its collar 4 lifted through the hole 2, after which the latch may be swung back to the position shown in full lines, and therefore the pin will remain in elevated position irrespective of the parts yet to be described.

Hingedly mounted at 10 in the top of the mouth M is a plate 11 extending normally obliquely downward and rearward and intended to be struck by the approaching link (not shown), and the lower end of this plate is connected by a pair of links 12 with a dog 13 standing above the draw head H and in rear of the pin 3. The links reach this dog through openings 14 in the top of the draw head, and they extend 85 through these openings on opposite sides of the pin as will be clear. The dog has at its rear side a headed stud 15 traveling in an upright slot which is formed in a guide 16 constituting part of the framework 1 as 90 best seen in Fig. 1. The dog may also carry a loop 17 which incloses a boss 18 rising from the draw head at the forward side of the pin, and on which boss rests the collar 4 when the parts stand in their normal position as seen in Fig. 2. This boss is cut away at its rear side so that the dog normally underlies the collar. Now when a link approaches and strikes the plate 11, the parts swing as the hinges 10 permit, and the links 12 cause the dog to rise, its headed stud traveling in the slotted guide 16. The dog engaging beneath the collar 4 pushes the pin upward, its lower end rising to permit the entrance of the link and the collar 105 finally reaching the position shown in dotted lines in Fig. 2. Means must now be provided to trip the dog from beneath the collar, and therefore we come to the next feature of the invention.

Upstanding from the rear portion of the dog is a tail 20 which, when the dog is moved upward is projected into a loop 21 carried at the upper end of a rock lever 22.

The latter is pivoted at 23 within the framework, and its upper end is borne normally forward by a spring 24. Its lower end is connected by a link 25 with another rock 5 lever 26 pivoted at 27 within an opening in the rear portion of the draw head H, and therefore as the link enters the latter its inner end pushes on this rock lever 26, the link 25 causes reverse movement of the upper 10 rock lever 22, and the loop 21 is moved to the rear just at a time when the tail 20 stands within the same. The result is that the dog is turned on its pivotal connection with the two links 12, and is withdrawn 15 from beneath the collar 4; and therefore the pin may now descend when its lower end will pass through the inner end of the link while the latter at this time of course stands well within the opening in the draw head H. 20 Therefore the coupling action of this device is entirely automatic. Uncoupling is done by raising the pin manually by means connected with the link or eye 5 at its upper end. I have already explained how the pin 25 can be raised and held raised by means of the latch 7, when it is desired to throw the automatic features of this device out of action. The parts are of the desired proportions and materials, and changes in details 30 can be made without departing from the principle of this invention.

What is claimed as new is:

1. In a car coupling, the combination with a vertically movable pin mounted through 35 the draw head and having a collar at its mid-length, a framework superposed upon the draw head and having a guide for the upper end of said pin and an upright slotted member adjacent said pin, and a latch mov- 40 ably mounted on the top of the framework and adapted to engage beneath said collar when the pin is raised; of a dog having a headed stud slidably mounted within said slot, the dog normally underlying said col- 45 lar, means for causing the rise of the dog by the entry of the link in the mouth of the draw head, and means for tilting the dog to disengage it from the collar after the pin has been raised.
- 50 2. In a car coupling, the combination with a draw head having an upright pin-opening and other openings at the sides thereof, a pin mounted slidably in the pin-opening and having a collar above the draw head, 55 and a framework superposed upon the head and having an upright guide; of a plate hinged within the mouth of the draw head, a pair of links extending from the plate upward through the side openings astride 60 the pin, a dog slidably mounted within said guide and normally underlying said collar, the upper ends of said links being pivoted to the dog, and means for tilting the latter 65 when it has reached its highest limit of movement, for the purpose set forth.

3. In a car coupling, the combination with a draw head having an upright pin-opening and other openings at the sides thereof, a pin mounted slidably in the pin-opening and having a collar above the draw head, 70 and a framework superposed upon the head and having an upright guide; of a plate hinged within the mouth of the draw head, a pair of links extending from the plate upward through the side openings astride 75 the pin, a dog pivoted to the upper ends of said links and normally underlying the collar, the dog having a headed stud moving in said guide and an upstanding tail, and mechanism actuated by the insertion 80 of a link into the mouth of the draw head for drawing on said tail to tilt the dog, for the purpose set forth.

4. In a car coupling, the combination with a draw head having an upright pin-opening 85 and other openings at the sides thereof, a pin mounted slidably in the pin-opening and having a collar above the draw head, and a framework superposed upon the head and having an upright guide; of a plate hinged 90 within the mouth of the draw head, a pair of links extending from the plate upward through the side openings astride the pin, a dog pivoted to the upper ends of said links and normally underlying the collar, the dog 95 having a headed stud moving in said guide and an upstanding tail, a loop at the upper end of said guide and into which said tail is adapted to be projected when the collar is raised, a rocking lever carrying said loop, 100 and mechanism at the rear of the mouth of the draw head for actuating said rocking lever by the entry of the link, the whole for action substantially as described.

5. In a car coupling of the type described, 105 the combination with a skeleton framework mounted on the draw head and having an upright slotted guide, a pin movable through said framework and through the draw head and having a collar at its mid- 110 length, a tilting dog normally standing beneath said collar and movably mounted within said guide, the dog having an up- standing tail, and mechanism within the mouth of the draw head for raising said dog 115 by the projection of a link thereinto; of a rock lever pivoted within said framework and having a loop at its upper end adapted to be engaged by said tail, a second rock lever mounted within the rear portion of 120 said mouth and adapted to be actuated by the link, and connections between said rock levers for the purpose set forth.

In testimony whereof I affix my signature in presence of two witnesses.

THOMAS WHITE.
